UNITED STATES PATENT OFFICE.

GEORGE H. DAY, OF SOUTHERBRIDGE, MASSACHUSETTS, ASSIGNOR TO AMERICAN OPTICAL COMPANY, OF SOUTHERBRIDGE, MASSACHUSETTS, A CORPORATION OF MASSACHUSETTS.

REEL FOR EYEGLASSES.

974,477.

Specification of Letters Patent.

Patented Nov. 1, 1910.

Application filed January 23, 1907. Serial No. 353,598.

To all whom it may concern:

Be it known that I, GEORGE H. DAY, a citizen of the United States, and a resident of Southbridge, county of Worcester, State of Massachusetts, have invented certain new and useful Improvements in Reels for Eye-glasses, of which the following is a specification.

My invention relates to eye glass reels and 10 has for its object to improve and simplify the construction thereof.

My invention will be fully described hereinafter and the features of novelty will be pointed out in the appended claims.

Reference is to be had to the accompanying drawings in which

Figure 1 is a rear elevation, of my improved reel; Fig. 2 is a similar view with the back plate removed; Fig. 3 is a sectional view on the line 3—3 of Fig. 4; Fig. 4 is a 20 sectional view on the line 4—4 of Fig. 1, on an enlarged scale and Fig. 5 is a face view of the back plate looking from the front.

A is the back plate which is provided 25 with a flange B and lugs or ears C. A cover D is adapted to engage the flange B of the back plate, and is provided with notches E into which the lugs or ears C of the back plate are arranged to fit, so that the cover is 30 incapable of being rotated relatively to the back plate. The cover D is provided with an inwardly extending tube F which is carried by said cover. This tube F is internally screw-threaded to receive the screw-threaded center-post G which is provided 35 with a smooth bearing portion G', the purpose of which will be more fully described hereinafter.

It is to be understood that if desired the 40 center-post may be otherwise secured to the cover D than described above.

H is a flat ring having a circumferential lip H' which forms a receptacle for the actuating spring I. One end of said spring first 45 passes through slot H² in the lip H' toward the outside and then through another slot H³ in said lip toward the inside, the end of said spring being thus held securely in position. The other end of the spring is fastened to one of a series of projections F' on the tube F as clearly shown in Fig. 3. The 50 projections F' are carried by the tube F. Instead of fastening the ends of the spring as described, the said ends may be simply riveted in position or any other convenient

means of fastening may be used. The ring H is further provided with a portion H⁴ which frictionally engages the periphery of the disk or center piece J. K is another ring having a portion K' bent at right angles and adapted to engage the portion H⁴ of the member H. The rings H, K, and disk J thus form the reel proper and are held together by friction or, if desired, may be otherwise secured together, as for instance 60 by soldering. The cord or chain L, one end of which is suitably fastened to the reel, is wound on the portion K' between the rings K and H.

G² is a stationary ratchet which forms 70 part of, or is secured to the post G. A screw M passes through a central opening A' in the back plate A, into the portion G' of the post G which is internally threaded for the reception of said screw. This screw M thus 75 serves to hold the parts together and the ratchet G² serves to prevent the reel disk J from leaving the smooth portion G' of the post G. A suitable opening D' is provided in the cover D for the cord or chain L to 80 pass through, the end of which cord or chain has secured to it the snap hook N, which may be of any desired form.

O is a retaining pawl pivoted to the member J at O' and is maintained in engagement with the ratchet G² by means of gravity, the end O² being extended to give it more weight for this purpose. A portion of the back plate A is pressed outward to form a sleeve or socket as indicated at A² by 90 means of which the pin P is secured to the said back A. This pin forms a means for attaching the device to the garment of the user, and is so positioned with respect to the pawl and ratchet as to insure the device 95 being properly fastened in position to obtain the best results.

It is to be further understood that the post G is preferably threaded in a direction opposite to the spring pressure or in other 100 words is so threaded that the pressure of the spring will have a tendency to tighten said post and prevent said post from backing out or becoming loosened.

I claim:

1. The combination of a cover, a back plate, an internally threaded center post secured to the cover, a reel mounted to turn on said post, a spring connected with the reel, a pawl carried by the reel, a stationary 110

105

ratchet carried by the center post and engaged by the pawl, and a fastening screw the shank of which engages and extends through the back plate and ratchet into the center post, the said screw engaging the back plate to force it toward the center post.

2. The combination of a casing composed of cover and back plate, an internally threaded tube secured to one of the parts of 10 the casing, a center post having one end externally screw-threaded to fit said tube, and the other end internally screw-threaded, a reel mounted to turn on said post, a ratchet stationary on the post, a spring 15 connected with the reel, a pawl carried by the reel and engaging the ratchet, and a fastening screw projected through the other part of the casing into the center post.

3. The combination of a casing composed 20 of cover and back plate, an internally threaded center post secured to one of the parts of the casing, a reel mounted to turn

on the said post, a spring connected with the reel, a pawl carried by the reel, a ratchet engaged by the pawl, and a fastening screw 25 projected through the other part of the casing into the center post, the said post being threaded in such a direction that the tension of the spring will operate to tighten it.

4. The combination of a casing having a screw threaded tube with a projection on the outside thereof, a center post screwed into said tube, a reel mounted to turn on said post, and a coiled spring having one end connected with the reel and the other secured 30 to said projection.

In testimony whereof, I have hereunto signed my name in the presence of two subscribing witnesses.

GEO. H. DAY.
